CLAIM

The ornamental design for a battery fuel gauge and hour meter as shown and described.

U.S. PATENT DOCUMENTS

DESCRIPTION

D226,024 S * 1/1973 Bell D10/22
D242,235 S * 11/1976 Redmann D10/102
D282,446 S * 2/1986 Gremonprez D10/30
D283,988 S * 5/1986 Krehel D10/101
D316,982 S * 5/1991 Hestich D10/85
D332,923 S * 2/1993 Polydoris D10/100
D357,880 S * 5/1995 Ueda D10/98
D509,764 S * 9/2005 Watson D10/98

FIG. 1 is a front, right and top perspective view of a battery fuel gauge and hour meter, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict portions of the battery fuel gauge and hour meter that form no part of the claimed design.
